[57] CLAIM

The ornamental design for a combined motor housing, blade irons and light fixture unit for a ceiling fan, as shown and described.

DESCRIPTION

FIG. 1 is a perspective view of a combined motor housing, blade irons and light fixture unit for a ceiling fan showing our new design;

FIG. 2 is an additional perspective view of the combined motor housing, blade irons and light fixture unit for a ceiling fan shown FIG. 1 with the environmental structure removed;

FIG. 3 is a front view thereof;

FIG. 4 is a right-side view thereof;

FIG. 5 is a rear view thereof;

FIG. 6 is a left-side view thereof;

FIG. 7 is a top view thereof;

FIG. 8 is a bottom view thereof;

FIG. 9 is a perspective view of a second embodiment of our new design for a combined motor housing, blade irons and light fixture unit for a ceiling fan;

FIG. 10 is a front view of FIG. 9;

FIG. 11 is a right-side view of FIG. 9;

FIG. 12 is a rear view of FIG. 9;

FIG. 13 is a left-side view of FIG. 9;

FIG. 14 is a bottom view of FIG. 9;

FIG. 15 is a top view of FIG. 9; and,

FIG. 16 is a perspective view of the combined motor housing, and blade irons portion of the combined motor housing, blade irons and light fixture unit for a ceiling fan, shown separately for clarity of illustration.

The broken line showing of environmental structure in FIGS. 1 and 16 is for illustrative purposes only and forms no part of the claimed design.
